N. J. Bernhard
ATTORNEY

UNITED STATES PATENT OFFICE.

JOHN A. KELLY, OF BROOKLYN, NEW YORK.

SHOE.

Application filed September 9, 1920. Serial No. 409,226.

This invention is a new article of footwear, the same being the product of a new and useful process of making shoes constituting the subject matter of a separate application Serial No. 409,225 for a patent filed by me on September 9, 1920, although it is to be distinctly understood that the new article may be produced by processes other than the particular or precise mode of procedure disclosed in said copending application.

According to this invention a stay composed of relatively narrow material is attached adjacent one edge thereof to an upper on a line adjacent the inner margin of said upper, and said stay is also attached with the upper to an outsole, the said two lines of attachment constituting permanent means for the union of the components of the article, and said stay affording a secure hold for the seam preferably used as the means for securing the outsole to the upper and the stay, whereby the stay acts to reinforce the upper so as to preclude the seam from pulling through said upper during the service of the shoe, particularly should the upper be composed of relatively thin or light weight material.

The resulting article is a single sole shoe of a flexible nature characterized by the presence of two approximately parallel lines of fastenings for the components of the shoe, one of which lines of permanent fastenings unites the upper and the stay directly, whereas the other permanent line of fastenings unites the stay, upper and outsole in such a manner as to produce what may be said to constitute a reinforced seam by which permanency is attained in the union of the outsole to the upper owing to the pressure of the stay provided in the inner surface of said upper for the express purpose of affording a secure hold for the outsole seam.

Other features and advantages of the invention will appear from the following description taken in connection with the drawings, wherein—

Figure 1 is a plan view of a temporary insole with a stay temporarily attached thereto.

Figure 2 is a plan view of the upper in lasted relation to a temporary insole and a permanent shank piece, said view being partly broken away to illustrate the stay

and said view illustrating a partial view of the outsole and illustrating also the seam and the stapling by which said outsole is united to the upper, the stay and the shank piece.

Figure 3 is a cross section on the line 3—3 of Figure 2 showing the stapling of the upper to the stay and the shank piece without attaching the upper directly to the temporary insole.

Figure 4 is a cross section through the upper and the shank piece on the line 4—4 of Figure 2.

Figure 5 is a cross section on the line 5—5 of Figure 2 illustrating the outsole and the dislodgment of the temporary insole.

Figure 6 is a cross section through the shank of the shoe.

Figure 7 is a cross section of another embodiment wherein the staples are concealed by a component of the stay in the fore part of the shoe.

A is the stay, B the temporary insole, C the shank piece, D the upper, D' a last, and F the outsole.

The stay is composed of a relatively thin and narrow piece of material, such as leather, fabric or other material suitable for the purpose.

The outsole F is shown as a single piece of material provided on that face thereof adapted in the completed article to be concealed by the upper, i. e., the inner face, with a channel f, said channel being cut or otherwise produced in the marginal portion of the outsole. As disclosed in my copending application, the material excised from the outsole to produce the channel may be and preferably is utilized for the production of the stay A.

The shank piece used is or may be of the form shown in Figures 4 and 6, the same being channeled at c and producing a lip c'.

As shown in Figure 5, the marginal portion of the upper lies in overlapping relation to the outsole, the said marginal upper portion being received within the channel f of the outsole. The stay A is in lapping relation to the inner margin of the upper, and this marginal portion of said upper is attached to the stay and to the shank piece by permanent fastenings, such as tacks, a seam, or by cement, the same being shown herein as staples E which are free from at-

- tachment, either directly or indirectly, to the temporary insole B. The staples E pass through the upper beginning at the shank piece and extending thence along the stay on one side of the shoe, around the toe, and thence extending along the other side of the shoe so as to attach the upper to the stay and the shank piece along both sides of the shoe and around the toe portion thereof, see 10 full and dotted lines in Figure 2. At the shoe shank, the staples pass through the upper and lip c' of the shank piece, whereas at the fore part of the shoe the staples pass through the upper and the stay at the free 15 inner marginal portion thereof.
- After lasting the upper and attaching it to the stay and the shank piece, the outsole F is assembled and attached, the preferred mode of attachment being by the aid of a 20 seam f which passes through the outsole, the upper and the stay at the fore part of the shoe and through the upper, the outsole and the shank piece at the shank portion of the shoe, all as clearly shown.
- 25 The temporary insole B is used in my process of making shoes as an aid in assembling the stay relatively to the last and to the upper, and for retaining the stay in position during the steps of lasting the upper and of stapling the upper to the stay and the shank piece; but this insole does not constitute an integral member of the 30 finished shoe, but on the contrary said insole is dislodged or withdrawn from the upper.

Under such circumstances, the stay is detachably connected by any desired means to the temporary insole, as e. g. by cementing, stitching or stapling, the stay to the insole, 40 but preferably the insole and the stay are separably connected by a chain stitch seam b, the same passing through the insole and the stay so as to leave free and unattached the two marginal portions of the stay, see 45 Figures 1 and 3 and the right hand portion of Figure 5.

The mode of producing the shoe will appear fully from the companion application to which reference has been made, but it 50 may be recited briefly as follows: The shank piece C, and the temporary insole B with the attached stay A, are assembled relatively to a last D', and the upper is then lasted, being temporarily fastened to the insole by 55 lasting tacks. The upper is now attached by staples E to the lip c' of shank piece C and to the inner marginal portion of stay A, after which the excess material of 60 the upper is cut or trimmed on a line parallel to and adjacent the edge of the stay and the line of the staples E, and thereafter the 65 trimmed or cut portion of the upper and the tacks are removed. An outsole is now assembled with respect to the upper and shank piece, and the several parts are at-

tached by stitching, the seam f passing through the outsole, the upper, the stay and the shank piece so that the line of stitching is approximately parallel to the line of stapling.

The temporary insole is now withdrawn from the upper, prior to which the chain stitch seam b is pulled out in order to detach the temporary insole from the stay; but while the dislodgment of said insole 70 has the effect of removing the tacks with the trimmed upper material from the upper, such removal of the insole has no effect upon the stay or the shank piece which remain permanent parts of the shoe, the said 75 stay being attached directly to the upper by the staples and being attached also to the upper and the outsole by the seam f.

In this connection it is desired to call attention to the fact that the seam f passes 80 directly through the stay and on a line exteriorly to the staples E, so that the stay is permanently attached to the upper and the stay affords added material to the upper 85 for securely holding the stitches by which 90 the outsole is attached to said upper, as a result of which added material the stitches cannot pull through the upper, which is a feature of material advantage in case the 95 upper is composed of relatively thin or light weight material.

As appears by reference to Figures 3 and 5, the stay is positioned on the inside of the outsole and covers that part of the margin of the upper lying within the channel f of said outsole, as a result of which 100 the line of fine wire staples E are exposed on the inner surface of the shoe. It may be, and sometimes is, desirable to cover the staples, in which case the stay is composed 105 of two layers of material A A', shown in Figure 7, said layers being in superposed relation. The two layers of material 110 composing the stay are fastened by the seam f to the upper and to the outsole, but only one 115 layer (layer A) is stapled to the upper, said staples E passing through the upper and through layer A to the exclusion of layer A', the latter layer A' being positioned in overlapping relation to the staples 120 E and effectually covering said staples and concealing the same so that the inner surface of the shoe is smooth and unbroken, the layer A' of stay material precluding the 125 staples from access to the foot when the shoe is in use.

Having thus fully described the invention, what I claim as new and desire to secure by Letters Patent is:

1. In a shoe, an upper, a stay in lapping 125 relation to a margin of said upper, an outsole, and two separate lines of fastenings, one of which unites one edge portion of the stay to the upper and the other of which 130 unites the opposite edge portion of the stay

to the upper and the outsole, said stay having one edge portion thereof attached fixedly and directly to the upper on a line inwardly of one row of fastenings which 5 unite upper and outsole.

2. In a shoe, an upper, an outsole, a stay composed of a strip of narrow material positioned in lapping relation to a margin of the upper, staples attaching the inner edge 10 portion of said stay directly to the margin of said upper, and a seam uniting the opposite edge portion of the stay to the upper and the outsole, said stay having one edge portion thereof attached fixedly and directly 15 to the upper on a line inwardly of the seam between upper and outsole.

3. In a shoe, a sole provided in the inner face thereof with a channel, a shank piece provided in the inner face thereof with a 20 channel extending toward the outer margin so as to produce a lip, a stay composed of narrow material separate from the sole and positioned to occupy the channel of said sole, an upper the marginal portion of which is 25 in lapping relation to the stay and to the lip of the shank piece, a row of fasteners attaching the marginal portion of the upper to the inner edge of the stay and to the lip of the shank piece, and a seam separate from 30 the row of fasteners and uniting the sole and the upper to the outer margin of the stay and to the lip of the shank piece.

4. In a shoe, an outsole provided on its inner face with a channel at the margin 35 thereof, an upper, a stay in lapping relation to said upper, said stay and the upper margin occupying said channel of the outsole, means for directly and fixedly attaching the inner edge portion of said stay to the upper,

and a seam uniting the outer edge portion of 40 the stay to the upper and the outsole.

5. In a shoe, an upper, a sole, a stay composed of narrow layers of material superposed one upon the other and one of which 45 layers is in contact with the upper adjacent the line of contact of said upper with the sole, means for fastening one layer of said stay material directly to the upper, and means uniting the sole to the upper and securing both layers of the stay material to 50 said upper.

6. In a shoe, an upper, a sole, a stay composed of superposed layers of material, staples attaching one layer of the stay material to the upper, and a seam uniting both 55 layers of the stay material to the upper and also attaching the sole to said upper, one of said layers covering the line of said staples.

7. In a shoe, an outsole provided on its inner face with a channel, an upper, a stay 60 composed of a strip of narrow material positioned in lapping relation to a marginal portion of the upper and in substantially flush relation to the inner face of the outsole, said stay and the upper margin being received 65 within the channel of said outsole, a row of permanent fasteners attaching the upper margin to the stay adjacent the inner edge thereof, and a seam passing through the upper and the otherwise unattached edge 70 portion of the stay for the attachment of the outsole, said stay and the seam constituting the sole means for the permanent union of the upper to the outsole.

In testimony whereof I have signed my 75 name hereto this 2nd day of September, 1920.

JOHN A. KELLY.
